UNITED STATES PATENT OFFICE

WILLIAM I. WEAVER, OF CAMDEN, NEW JERSEY

FIREPROOF PADDING

No Drawing.

Application filed October 11, 1929. Serial No. 399,099.

In flat work ironers, press machines and similar machines, where heat is applied through a drum, screen or other apparatus, it is essential and desirable to have the same covered with a sheet of padding or textile fabric, and it is essential not only that such padding or fabric should possess certain characteristics so that the inner plies of the fabric be loosely bound so as to form a spongy core, while the outside plies must be more firmly bound, but it is also essential that the said padding or fabric, where the same is placed next to such drum, screen or machine, shall be heat resisting. Otherwise, the fabric, where it touches that portion of such machine which is so heated, will become cooked, hardened or carbonized. The life of the fabric is much shortened by this carbonization. In order to avoid the cooking, hardening or carbonization and thus lengthen the life and use of any such fabric and still keep the fabric porous, I have invented a mixture or solution which is heat resisting. At the same time, the fabric must be kept flexible. In other words, it must have flexibility so that it will not crack or break when rolled or creased. It is also necessary that the heat resisting material be so applied that it shall not penetrate to the other side of the padding and yet it must also adhere to the side next to the heat, and so adhere in such a manner as not to be easily removed or easily rubbed off, while the machine is in motion, said solution also must be of such a nature as when applied to the fabric on the one side that it will not seal or close up the pores on that side so as to prevent entirely the heat from the ironer or machine passing through the fabric. Otherwise, the whole purpose of the solution and the usefulness of the fabric on flat work ironers and press machines would be gone. The solution is intended to make the fabric, on the side where it is applied, heat resisting, so that the life of the fabric may be prolonged, but it is essential that the heat from the ironer or machine shall pass through the fabric to the other side so as to absorb the moisture on such other side when such ironer or machine is in use. The fabric, therefore, after said solution is ap-

plied on the one side, must still remain porous. The padding or fabric to which my mixture is to be applied is most commonly used in laundries and other places where linens, cloths and other clothing materials are cleaned, pressed or manufactured. It is, therefore, also essential that the solution which shall be applied to the padding, shall be in its nature, cleanly and not easily removed. My solution, therefore, must have in particular, four qualifications—flexibility, heat resistance, the heat resisting material must have an adhesive quality and at the same time the solution must have fluidity so as to be easily applied by spraying or otherwise. The mineral matter must be non-igniting and of such a nature so as not to seal or close up that side of the fabric where applied. In other words the fabric must remain porous.

To the above ends my invention consists of a novel composition of matter composed of glycerine, a good adhesive and a suitable powdered fire proof or heat resisting nonigniting mineral material, the ingredients being preferably commingled in the manner hereinafter described with the addition of sufficient water so as to make the solution fluid and thus easily applied.

It further consists of a novel porous fabric or padding which is impregnated on one side with the foregoing solution in any suitable manner, preferably in the form of a spray propelled against and into the fabric by a suitable pneumatic means such as an air gun or the like.

It further consists in the novel porous padding or fabric conforming substantially to the disclosure in the Weaver Patent No. 1,471,224 heretofore granted to me, wherein is disclosed a novel padding fabric having interwoven superimposed plies composed of relatively small spaced hard twisted warps and relatively large spaced soft sliver-like interwoven wefts forming an internal yielding spongy mass, said fabric in accordance with my present invention being impregnated on one side with my novel composition of matter aforesaid.

My novel mixture is composed of the fol-

lowing ingredients which are combined, heated and boiled together in substantially the following proportions:

(a) Glycerine, about 2½ per cent.

5 (b) Glue sizing, gum shellac, paste or some other similar adhesive, about 16 per cent.

(c) Asbestos, whiting, powdered calcium, lime, chalk or other nonigniting mineral substance, about 28½ per cent.

10 (d) Water, about 53 per cent.

The glycerine in the mixture or solution gives to the padding or fabric, when applied, flexibility or pliability and so prevents it from cracking or breaking when rolled or bent. The asbestos, whiting, powdered calcium, lime, chalk or other nonigniting mineral matter in the mixture, when applied, makes the fabric fire proof or heat resisting and the glue sizing, gum shellac, paste or

15 other suitable adhesive, makes the mixture stick or adhere to the fabric. The water makes the solution fluid so that it can be easily applied by spraying or otherwise. The mineral matter must be nonigniting and of such a 20 nature so as not to seal or close up that side of the fabric where applied. All these four qualities are primarily necessary. The novel feature in the mixture is in the combination 25 of these four qualities.

30 It must be understood that the several materials in the combination of which my invention consists can be variously arranged and organized and that my invention is not limited to the precise materials or proportions 35 above named.

No mixture or solution in the trade has heretofore been invented or used in laundries, tailor shops or similar places where flat work ironers, press machines or similar machines 40 are in use, which will make the fabric, padding or other material to which it is applied fire proof or heat resisting on the under side thereof and at the same time keep it porous on that side and soft or spongy on the upper 45 side and yet flexible on both sides. As a matter of fact, no mixture or solution has ever been invented or used in any way similar to the mixture or solution above named, invented by me for the purposes aforesaid.

50 I am aware that it has heretofore been proposed in the German patent to Von Asten No. 275,020, June 4, 1914, to provide a facing of asbestos which is interwoven in the padding or the fabric, but my invention differs therefrom in the employment of the additional ingredients of glycerine, water and an adhesive, which in combination with the powdered fire proof material is sprayed upon or into the fabric on the under side. This spraying is 55 so done under my invention at a very material reduction in cost than if the fire proof material were interwoven into the fabric.

60 My novel composition of matter will be 35 found to be effective when it is sprayed upon or into any padding, fabric or textile material

having the general characteristics above described, but I have found it to be especially useful when sprayed upon or into a textile fabric or padding having a soft spongy interior and a relatively close tightly woven exterior as described in my patent aforesaid. 70

I am aware that slight changes in the above named mixture or solution may be made by those skilled in the art, since it is evident that other materials than those particularly enumerated may be used to form a mixture which, when applied to the padding or textile fabric to be used on flat work ironers, press machines or other machines, shall have the four particular qualifications above named, viz; flexibility, adherence, fluidity and heat resistance 80 and still remain porous on the side where the solution is applied. 75

85 My novel invention consists not simply in having certain materials, as I have above named, formed into a combination resulting in a mixture or solution similar to the one above mentioned, but the novelty or newness in my invention consists primarily in selecting materials for said solution which (a) 90 will keep the solution in a fluid state so as to be easily applied and which solution, when applied to the padding will (b) render it fire proof or heat resisting, (c) adhere thereto and (d) give to the padding or fabric flexibility or pliability and still keep the fabric 95 porous on the side where applied so that sufficient heat may pass through to the other side. 100

105 It will be apparent that for certain types of padding it is desirable that my novel solution or composition of matter be sprayed on or applied to only one side of the padding or other textile fabric. There may be other situations wherein it may be desirable to spray 110 my novel solution or composition of matter on both sides of such padding or fabric or to impregnate the body of the same as well as both sides thereof with said solution and I therefore desire it understood that my invention 115 in its broad aspects comprehends not only my novel solution or composition of matter, but said solution when sprayed or applied to one or both sides of said padding or fabric or to the body of the same, which 120 padding or fabric may be of any character having sufficient body or texture to enable it to be used under the conditions stated or said padding or fabric may have a soft spongy interior and a relatively more tightly woven exterior surface or surfaces substantially as in my patent aforesaid. 125

I am aware that the invention may be embodied in other specific forms without departing from the spirit or essential attributes thereof, and I therefore desire the present embodiment to be considered in all respects as illustrative and not restrictive, reference being had to the appended claims rather than to 130

the foregoing description to indicate the scope of the invention.

Having thus described my invention, what I claim is new and desire to secure by Letters Patent, is:—

- 5 1. A new article of manufacture adapted for use on flatwork ironers, press machines and other similar ironing and pressing machines consisting of a porous flexible fabric, one side only of which fabric having applied thereto a solution consisting of glycerine, water, an adhesive and a powdered, heat resisting, nonigniting, mineral material.
- 10 2. A new article of manufacture adapted for use on flatwork ironers, press machines and other similar ironing and pressing machines, consisting of a porous flexible padding or textile fabric having a soft spongy interior and exterior plies of relatively closely interwoven warps and wefts, said padding or fabric being impregnated on one side only with a solution consisting of glycerine, water, an adhesive, and a powdered heat resisting, nonigniting mineral material.
- 15 3. A new article of manufacture adapted for use on flatwork ironers, press machines and other similar ironing and pressing machines consisting of a porous flexible textile fabric having a soft spongy interior, one side only of which fabric having applied thereto a solution consisting of glycerine, water, an adhesive and a powdered, heat resisting, nonigniting, mineral material.
